UNITED STATES PATENT OFFICE

PATRICK McLOUGHLIN, OF WORCESTER, MASSACHUSETTS

REPAIR LINK

Application filed December 12, 1928. Serial No. 325,579.

This invention relates to a repair link for use on anti-skid tire chains.

The object of the invention is to provide a simple and convenient repair link of such a nature that its free end will yield to allow a chain link to pass into it and will then spring together sufficiently to prevent removal accidentally or without the application of force in a certain direction and to provide a construction in which the weight of the car and tire will not be depended upon to close the link and in fact the link does not have to be closed at all.

Other objects and advantages of the invention will appear hereinafter.

Reference is to be had to the accompanying drawings in which

Fig. 1 is a plan of one form in which this repair link can be constructed;

Fig. 2 is a side view of the same;

Fig. 3 is an end view;

Fig. 4 is a plan of a modified form of the link; and

Fig. 5 is an end view thereof.

In the form shown in Figs. 1, 2 and 3, the link consists of a single piece of wire, preferably round in cross section. The whole link is made as near as possible in a single plane. The link comprises a straight side 10 adapted to lie flat against the tire or flat on the ground. This is provided with a coil 11 at the end to provide the amount of resiliency that may be required and then the coil is curved into a side 12 parallel with the free side 10 and in the same plane except insofar as it has to be lifted a little at the rear to form a continuation of said coil.

At the free end of the side 12 is a transverse end 13 which is curved inwardly to form a bend or hook 14 inside at the end. This bend also lies substantially in the plane of the rest of the link. The convex surface 15 of this bend is located at such distance from the free side 10 that the wire of a link of a cross chain will not pass between them either inwardly or outwardly without the application of enough force thereon to swing these two ends 10 and 15 apart. When the cross chain link, such as 16, is forced in by the application of enough pressure, these

two ends spring back toward each other again and thus automatically hold it in its original position. Usually the wire of the cross chain link is of the same diameter as that of the repair link.

In the use of the device the link 16 which is inserted in this way might be pulled out at the end by a strong pull but such an accident is not likely to happen. However, the bending inwardly of the end 14 provides a hook and the link 16 normally passes over the end of this hook and is engaged behind the transverse end 13 and behind the hook 14 so that it does not depend upon the resiliency of the wire to hold it in position. Nevertheless when it is desired to remove the link 16 it can be placed in the space between the side 10 and surface 15 and pulled outwardly, flexing the side 10 for that purpose and no other force has to be applied to it.

When the link is removed the parts spring back to their original position and are in proper condition for use again. In this way it will be seen that there are no parts projecting outwardly that are likely to dig into the tire or wheel no matter which side up the repair link is placed, that there are no parts in intersecting planes, thus providing projections sticking out and apt to cause damage and that the two sides 10 and 12 are substantially parallel with each other.

The same idea can be carried out in other ways and in Fig. 4 I have shown a link having the parts 10, 13, 14, 15 and 16 similar to those described above. In this case two changes are made. In the first place no coil is provided, the natural resiliency of the wire being relied upon as sufficient. Furthermore, the end 14 sticks up above the plane of the rest of the link but only to such an extent as to provide a passage between the surface 15 and the end 10 of just the right size and to provide this in a substantially vertical plane instead of a horizontal plane as shown in Fig. 1. This link is less expensive to make than the one shown in Fig. 1 but has less resiliency and it sticks up out of the plane of the link somewhat and might tend to wear the tire a little. The

convex surface 15 is the one that would engage the tire instead of the square end of the link itself, so not much trouble is likely to come from this construction. Furthermore, it is bent out of the plane only a distance equal to twice the diameter of the wire of which the link is made and in fact slightly less than that. The wire preferably is made of a quality which has considerable resiliency and otherwise the bend 14 would be forced down on the side 10 by continued usage and it would be very difficult to get the chain link out of it or to use it again.

In all these forms the link is made of spring wire, although a comparatively inexpensive grade of such wire can be used. The link is sold at retail in a closed condition, that is, with the ends near enough together so that a chain link can be put on it or taken off with the application of enough pressure to force the ends wide apart. They spring back together after the chain is applied and after long use the link is intended to have the same shape as when sold. The shape is not changed by the passage of the car over it. Nevertheless if such a change takes place it does not affect in any way the holding qualities of the link for the cross chain on which it is applied but would only affect its utility in case it was desired to remove it or use it over again but these links are so cheap they seldom are used a second time.

Although I have illustrated and described only two forms of the invention I am aware of the fact that other modifications can be made therein by any person skilled in the art without departing from the scope of the invention as expressed in the claims.

40 Therefore, I do not wish to be limited in this respect but what I do claim is:—

1. As an article of manufacture, a cross chain repair link comprising a free side and a side integrally connected with it and arranged opposite and substantially parallel with it and substantially in the same plane, a transverse end extending from said opposite side to the vicinity of the first named side, but spaced therefrom, the space between said end and side extending in the same direction as the free side and being a little less in width than the diameter of a chain link to be attached, said repair link being formed of spring wire, whereby the chain link can be applied to it and removed from it by forcing it through the space between the end and side and the link will return to normal condition thereafter.

2. As an article of manufacture, a repair link for cross chains comprising a straight side, an opposite side integrally connected therewith, a transverse end extending from said opposite side nearly but not quite to the first named side at the end thereof, terminating in a bend inwardly extending from the

end of the link, said parts being substantially in one plane and being formed of a single piece of spring wire, the distance between the adjacent surfaces of the convex side of said bend and straight side being slightly less than the diameter of the wire of the chain link to be connected, the space between the bend and straight side opening at the end of the link in alignment with said straight side for the purpose described.

3. As an article of manufacture, a repair link comprising a side of spring wire having an integral coil at the end opposite its free end, said coil terminating in a side having at its opposite end an integral end member extending toward the extreme free end of the opposite side, the space between the nearest surface of said end and the first named side being less than the thickness of the wire of which it is formed.

4. As an article of manufacture, a repair link comprising a straight side of spring wire having an integral coil at the end opposite its free end, said coil terminating in a side parallel with said side, the opposite side having at its end an integral transverse part bent reversely inwardly to form a hook, the space between the convex surface of said hook and the first named side being less than the thickness of the wire of which it is formed, whereby a chain link formed of wire of the same gauge can be attached or removed by forcing it into the space enough to flex the ends of the link apart temporarily.

In testimony whereof I have hereunto affixed my signature.

PATRICK McLOUGHLIN.
